PRESS BOX LATCH

Filed Aug. 13, 1928

UNITED STATES PATENT OFFICE

JOSEPH BEHLE, THOMAS W. AVEN, AND HUGO LINNARTZ, OF DALLAS, TEXAS, ASSIGNEES TO THE MURRAY COMPANY, OF DALLAS, TEXAS, A CORPORATION OF TEXAS

PRESS BOX LATCH

Application filed August 13, 1928. Serial No. 299,314.

This invention relates to new and useful improvements in press box latches.

One object of the invention is to provide an automatic latch for holding a press box against rotation and for centering the box under the platen.

Another object of the invention is to provide a latch keeper capable of adjustments for compensating the variations in the elevation, tilting or rotation of the platform and box.

A further object of the invention is to provide a latch that will be simple and economical to construct and which will comprise a few number of parts; and also one which may be locked out of operative position, thus permitting a free rotation of the platform.

A construction designed to carry out the invention will be hereinafter described, together with other features of the invention.

The invention will be more readily understood from a reading of the following specification and by reference to the accompanying drawings, in which an example of the invention is shown, and wherein:

Fig. 1 is an elevation of a latch constructed in accordance with the invention, the keeper being omitted,

Fig. 2 is a side elevation of a portion of a press box and frame equipped with such a latch and keeper,

Fig. 3 is a front elevation of the keeper,

Fig. 4 is a plan view of the same,

Fig. 5 is a longitudinal sectional view taken on the line 5—5 of Fig. 4,

Fig. 6 is a transverse sectional view taken on the line 6—6 of Fig. 4, and

Fig. 7 is a plan view of the supporting bracket.

In the drawings the numeral 10 designates a bracket for support which is preferably, but not necessarily, cast integral with the end channel bar 11 of a press box 12 and located intermediate the ends thereof. This bracket includes a countersunk flat top or shelf 10' directed outwardly from the bar 11 and braced at each end by vertical webs 10a. On the shelf 10' of this bracket is mounted

a horizontal keeper plate 13 which extends outwardly from the end of the press box.

The keeper plate overhangs the shelf and has a central notch 14, while its ends are rounded at 15. On the frame upright 16 is mounted a latch hanger 17 having a back plate 18 provided with vertical slots 19. Stud bolts 20 extending through the slots are screwed into the inner side of the upright, whereby the plate is held securely against the upright and vertical adjustment of the hanger is thus obtained.

The hanger also includes a pair of outwardly directed ears 21 extending from the back plate and braced by webs 22, said ears overhanging the keeper plate 13. An inverted bell-crank latch lever 23 is pivoted between the ears on a bolt 24, whereby one leg of the lever depends vertically between the front portions of the ears and the other leg extends inwardly toward uprights at the tops of the ears.

The depending leg of the lever is forced outwardly by a coiled spring 25 confined between the ears. The lower end of the lever hangs below the hanger and is reduced so as to more readily engage in the notch 14. A handle bar 26 is loosely journaled on a stud 27 on the inner side of the upright and is pivotally connected to the upper end of a rod 28 pivoted to the end of the upper leg of the latch lever, so that when said bar is depressed the rod will be lifted, whereby the lever 23 will be swung and withdrawn from the notch 14 of the keeper. When so depressed, the handle bar may be engaged under a lug 29 on the edge of the upright.

When the handle bar is released from the lug 29 the spring will swing the latch lever into the path of the keeper plate. Thus when the box 12 is rotated one of the corners 15 will engage the lower end of the lever and slightly depress the same, so that the edge of the plate will ride along the lever until the latter drops into the notch 14 and locks the box in position. When it is desired to rotate the box, the handle bar 26 is depressed and engaged under the lug, whereby the latch 23 is withdrawn from the notch 14.

It is essential that a close relation between the plate 13 and the hanger 17 be maintained; also that the box be centered under the top platen bars (not shown) when locked. The platform on which the box is mounted is subject to variation in its movements, due to wear and strains, and therefore, the latch parts may require adjustments to maintain their proper relation.

16 The plate 13 is provided with longitudinal slots 30 crossing slots 31 in the shelf 10' and both receiving bolts 32, whereby the plate is made freely adjustable in a horizontal plane on the shelf. Lugs 33 depending from the ends of the plate 13 carry set screws 34 engaging webs 10a, whereby the plate may be shifted longitudinally, when the bolts 32 are loosened, and also whereby the plate may be fastened against longitudinal movement.

20 The shelf 10' has a plurality of set screws 36 bearing against the bottom of the plate 13 and capable of adjustment for raising or lowering the plate. This vertical adjustment coupled with the vertical adjustment 25 of the hanger 17 enables the parts to be set so that the keeper plate will swing under the hanger in close relation thereto, but without binding. The adjustments of the 30 plate permit its location at such a position as to center the box under the platen bars, when the lever 23 engages in the notch 14. Various changes in the size and shape of 35 the different parts, as well as modifications and alterations, may be made within the scope of the appended claims.

What we claim is:

1. In a press box latch device, a keeper for mounting on a press box, means for 40 adjusting the keeper to compensate variations in the position of the box, and a latch for mounting on the press frame in the path of the keeper.

2. In a press box latch device, a keeper for mounting on a press box, a hanger for 45 mounting on a press frame and including a pair of ears, a bell-crank latch lever pivoted between said ears of the hanger, a coiled spring on the hanger engaging the lever, a handle bar, and a connection between the lever and the bar.

3. In a press box latch device, a bracket for mounting on a press box, a keeper plate 50 mounted on the bracket and having a notch, means for adjusting the plate in two directions, and a spring pressed latch lever for mounting on a press frame and engaging the notch of the plate.

60 4. In a press box latch, a latch lever, a bracket for mounting on a press box and 55 including a shelf, a keeper plate having a notch in its front edge for receiving the latch lever, and means for adjustably securing the plate on said shelf, whereby said

plate may be shifted in vertical and horizontal directions.

5. The combination with the end of a press box and the upright of a press frame, of a support mounted on the end of the press 70 box, a keeper member mounted on the support and projecting outwardly from the end of the box, a hanger on the inner side of the frame upright, a latch carried by the hanger in position to engage the keeper, 75 and means for operating the latch.

6. The combination with the end of a press box and the upright of a press frame, of a support mounted on the end of the press box, a keeper member mounted on the support and projecting outwardly from the end of the box, a hanger on the inner side of the frame upright, a latch carried by the hanger in position to engage the keeper, 80 a lever pivoted on the frame upright, and an operating connection between the lever 85 and the latch.

7. In a press box latch device, a latch having means for adjustably mounting it on a press frame, means for operating the latch, and a keeper having means for adjustably mounting it on the end of a press 90 box in the path of the latch.

8. In a press box latch device, a keeper for mounting on the end of a swinging press box, a hanger for mounting on the press frame, a latch lever pivoted on the hanger in position to engage the keeper to hold the box against swinging, a spring for urging the latch lever into engagement with the keeper, means for withdrawing the lever from the keeper, and means for locking the lever out of engagement with the keeper, 95 whereby the press box may be freely swung.

9. In a press box latch device, a mounting for the end of a swinging press box, a keeper shiftable on the mounting laterally of the press box, and a latch for mounting on the press frame for engaging the keeper.

In testimony whereof we affix our signatures.

JOSEPH BEHILE.
THOS. W. AVEN.
HUGO LINNARTZ.
